ABSTRACT: The stand of the invention is intended to provide rotatable support for heavy reels such as reels of electric wire or telephone cable. The stand comprises a base having a peripheral tire member which serves as the ground-engaging member. A central socket member is removably secured to the base, and this socket member rotatably and detachably receives a spindle forming an integral part of a reel-supporting platform. A reel of wire or cable is adapted to be positioned flatwise on the platform, and the wire or cable can be freely unwound therefrom. The rotatable platform has an upwardly extending post for holding a reel on the platform. The base and inflated peripheral member may comprise a conventional wheel and tire.

FIG. 1

FIG. 2

PERRY E. LANDSEM
INVENTOR.
BY *Eugene M. Aebelmann*
ATTY.

REEL-HOLDING STAND

BACKGROUND OF THE INVENTION

Reels for holding electric wire, telephone cable or other line are extremely heavy and usually require special equipment for supporting them rotatably so that the line can be unwound therefrom. That is, in connection with unwinding the line from the reels, special stands are necessary to raise the reel off the ground or truck bed in order to permit rotation thereof. Such stands are expensive and cumbersome and are difficult to manipulate.

SUMMARY OF THE INVENTION

According to the present invention and forming a primary objective thereof a reel-holding stand is provided which is simple in construction and yet provides an efficient rotatable support for a reel such that a line can be unwound therefrom.

Another object is to provide a reel-holding stand of the type described having a novel structure employing a base portion on which a rotatable platform is supported and having a peripheral tire member which supports the base portion off the ground as well as providing cushioned support for the base and frictional contact with the ground.

Still another object is to provide a reel-holding stand of the type described having a novel base portion which may include a conventional vehicle wheel and tire as a part thereof.

The invention will be better understood and additional objects and advantages will become apparent from the following description taken in connection with the accompanying drawings which illustrate a preferred form of the device.

BRIEF DESCRIPTION OF THE DRAWINGS

FIG. 1 is an elevational view of the present reel-holding stand showing a reel supported thereon and cable being unwound from such reel; and

FIG. 2 is also an elevational view but is enlarged relative to FIG. 1 and is partly broken away for clarity.

DETAILED DESCRIPTION OF THE PREFERRED EMBODIMENT

Referring in particular to the drawings, the numeral 10 designates a conventional reel for holding electric wire, telephone cable, or other line. Such reels are spool-shaped and have end walls 12 and an axial opening 14. Wire wound on such spool is designated by the numeral 16.

The invention resides in a stand providing free rotatable support for the reel 10 so that wire or cable thereon can be unwound conveniently. Such holder comprises a horizontal base portion 18 provided with a rim 20 on which is mounted a tire member 22. As is apparent, the lower portion of the stand may comprise a conventional vehicle wheel wherein the base portions 18 and 20 are the wheel and rim, respectively, and the peripheral member is the tire. The base portion 18 has a central circular opening 24 and if the lower portion of the stand comprises a conventional wheel, the opening 24 comprises the hub-receiving opening.

An elongated cylindrical socket or adapter member 26 having a central bore 27 is fitted in the opening 24 and has a circular outer flange 28 intermediate its ends adapted to seat on the base portion 18. Flange 28 has threaded holes 30 adapted to receive attaching screws 32 projecting upwardly through holes 34 in the base 18. The holes 34 in the wheel plate 18 may comprise the lug screw receiving holes if the device uses a conventional wheel as the lower stand portion, and the attaching screws may comprise the existing wheel-attaching lug screws, in which case the holes 30 in the flange 28 would necessarily be located for alignment with the holes 34 and have suitable size and threading to receive the lug screws. The socket member 26 has a flat upper surface 35.

A reel supporting platform 36 is rotatably supported on the socket member 26, and such platform has a base portion 38 with a flat bottom surface 40 in bearing engagement with the

flat upper surface 35 of the socket member 26. Base portion 38 of the reel-supporting platform has an integral depending spindle 42 rotatably engaged in the central bore 27 of the socket member 26.

Platform 36 has a dish-shaped plate 44 which leads integrally from the base portion 38, the concaved side of the plate 44 being disposed upwardly and the uppermost edge thereof projecting above the top surface of the tire 22 whereby a reel 10 is adapted to rotate freely above the tire. A central post 46 extends integrally upwardly from the base portion 38 of the platform and is arranged to be received in the central bore 14 of a reel 10 to hold the latter centered on the present device.

In accordance with the present invention, there is provided a simplified and inexpensive yet very functional stand for holding large reels of lines such as wire or cable for rotation. The reel-holding stand is easily handled in that it can be rolled to its location if necessary. The platform 36 is detachable therefrom by lifting it off the base portion.

As stated above, the socket member 26 is adapted to project through the usual central opening in a wheel and the bores 30 in the flange 28 are selectively located so that attachment of the present holder to a wheel is accomplished by the conventional lug screws 32.

The present invention thus facilitates formation of the base portion of the stand from a vehicle wheel such as from an old discarded truck wheel, thus contributing to its economy of manufacture. The tire 22 also may comprise a discarded tire, it being preferred, although not necessary, that it be capable of holding air. As in the usual wheel assembly, the tire 22 has a greater thickness than the rim whereby the tire is in engagement with the supporting surface to provide a frictional grip with the latter as well as cushioned support. For the purpose of placing a reel on the present stand for unwinding from a position wherein it is positioned on its edge, the stand is tipped up and its post 46 inserted in the central bore 14 of the reel. Then the assembly is flopped over with the stand at the bottom.

It is to be understood that the form of my invention herein shown and described is to be taken as a preferred example of the same and that various changes in the shape, size and arrangement of parts may be resorted to without departing from the spirit of my invention.

Having thus described my invention, I claim:

1. In combination, a spare vehicle wheel having a body portion and a rim on said body portion, a tire on said rim, said body portion having a plurality of apertures which normally receive lug bolts of the wheel, an adapter member having upper and lower ends and also having a central bore, said adapter member having apertures located selectively for alignment with the apertures in said body portion, bolt means engageable in the apertures of said body portion and said adapter member to secure said adapter member to said body portion, a dish-shaped platform member supported rotatably on the upper end of said adapter member with the concaved side thereof facing upwardly, an integral depending spindle on said platform journaled in the bore of said adapter member, and a post projecting upwardly from said platform arranged to extend into a bore of a reel arranged to be supported on said platform and rotatable therewith.

2. In combination, a spare vehicle wheel having a body portion and a rim on said body portion, a tire on said rim, means in said body portion defining a central opening which normally receives a wheel hub, said body portion having a plurality of apertures around said central opening which normally receive lug bolts of the wheel, and adapter member received in said central opening and having upper and lower ends and a central bore, an outwardly projecting lateral flange on said adapter member disposed intermediate the upper and lower ends of the latter and being engageable on said body portion to support said adapter member on said body portion with a portion of said adapter member disposed in the central opening of the wheel, said flange extending laterally beyond said plurality of apertures, means in said flange defining a plurality

of apertures located selectively for alignment with the said apertures in the body portion, bolt means engageable in the apertures of said body portion and said flange to connect said adapter member securely to said body portion, a dish-shaped platform member supported rotatably on the upper end of said adapter member with the concave side thereof facing up-

wardly, an integral depending spindle on said platform journaled in the bore of said adapter member, and a post projecting upwardly from said platform arranged to extend into a bore of a reel arranged to be supported on said platform and rotatable therewith.
